SIGNAL RECEIVING APPARATUS

George Lisle Beers, Collingswood, N. J., assignor, by mesne assignments, to Radio Corporation of America, New York, N. Y., a corporation of Delaware

Application January 31, 1931, Serial No. 512,653

32 Claims. (Cl. 250—20)

My invention relates to signal receiving apparatus and it has particular relation to devices for preventing the response of such apparatus to signals of amplitude less than a predetermined value.

It has, previously, been proposed to provide signal-receiving apparatus with automatic volume-control devices whereby the ultimate sound output is rendered substantially independent of fading and other phenomena which tend to cause the amplitude of an incoming signal to greatly vary. In the operation of receivers equipped with automatic volume-control devices, however, some dissatisfaction has been experienced by reason of the fact that, during the operation of manually or automatically tuning the system from one desired station to another, intervening stations are received. Furthermore, during the tuning operation, there is always present, from a wide variety of sources, objectionable interference of the type generally designated as "background noise".

It is, accordingly, an object of my invention to provide means whereby a portion of a radio receiver is rendered inoperative during the tuning operation.

Another object of my invention is to provide means whereby background noise shall be eliminated during the operation of tuning a signal receiving system from one desired station to another station.

Another object of my invention is to provide, in a signal receiving system of the type including automatic volume-control devices, means responsive to said devices for eliminating background noise.

A further object of my invention is to provide, in a system of the type described, means that shall give a visual indication of the tuning of the system to exact syntony with signals from a desired station.

A still further and more specific object of my invention is to provide, in a system of the type described, wherein a tuning indication device is included, means for illuminating the said device at such times as the system is being tuned to syntony with a desired signal and additional illuminating means for indicating that the said desired signal is being received at predetermined amplitude.

The aforementioned objects and other objects appurtenant thereto, I prefer to accomplish through the medium of a grid-control rectifying device having characteristics similar to those of the device commercially designated as a Thy-

atron. In the General Electric Review for April 1929, page 213, devices of the character preferred as rectifiers are defined as electrostatically controlled arc rectifiers and such term will be used hereinafter to refer to that type of device or tube. The rectifying device is supplied with alternating potential and the grid thereof is normally so biased that rectified current flows in the output circuit. The grid of the rectifier device is so connected to the plate terminal of a resistor included in the output circuit of a volume-control tube, that the drop in potential across the said resistor, when current flows therein, shall compensate the normal bias applied to the device with the result that it becomes non-conductive.

The volume-control tube is supplied with signal energy from amplifiers which precede it, the presence of a signal of proper amplitude causing the said tube to become more conductive than normal with the result that current flows in the output resistor referred to.

I further interpose a light-source in the output circuit of the rectifier or so arrange the said source that the application of energy thereto is controlled by current in the said output circuit and I so dispose the light-source that it illuminates at least a portion of the tuning-indication device during such times as a signal is being "tuned in".

The novel features that I consider characteristic of my invention are set forth with particularity in the appended claims. The invention itself, however, both as to its organization and its method of operation, together with additional objects and advantages, will best be understood from the following description of a specific embodiment and certain variants thereof, when read in connection with the accompanying drawing.

The single figure of the drawing is a diagrammatic view of a portion of a radio receiving system of the superheterodyne type including an embodiment of my invention.

The apparatus illustrated in the drawing comprises a volume-control tube 1, a rectifier device such as an electrostatically controlled arc rectifier providing a background noise suppressor tube 3 having characteristics hereinbefore referred to, and a second detector tube 5 which represents any suitable electric discharge amplifier device located in the signal circuit of the apparatus. The volume-control tube is provided with an input circuit constituted by an inductor 7 and a tuning condenser 9, one end of the in-

ductor being connected by a conductor 11 to the grid of the second detector tube 5 and the other end of the inductor being connected through a resistor 13 and a light-source 15, such as a small incandescent lamp, to a point 17 on a voltage dividing resistor 19 which is negative with respect to a point 21 on the same resistor to which the cathode of the second detector is connected.

A resistor 23 shunted by a condenser 25 is interposed between the cathode of the second detector tube and the point 21 on the voltage dividing resistor to which it is connected, the drop in potential across the first mentioned resistor, occasioned by the flow of space current therein, together with the drop between points 17 and 21, normally biasing the second detector to substantially the cut-off point.

The second detector is supplied with plate potential from the voltage dividing resistor 19, the primary winding 27 of an audio frequency transformer 29 being included in the supply circuit.

The light-source 15 referred to is also included in the output circuit of the rectifier, the said rectifier being supplied with plate potential from any convenient AC source (not shown).

The output circuit of the volume-control tube includes a resistor 31, one end of which is connected to the plate of the said tube and, through a resistor 32 to the grid of the rectifier, and the other end of which is connected to a point 33 on the voltage dividing resistor 19 which is at a positive potential with respect to a point 35 thereon to which a conductor 37, leading from the cathode of the volume-control tube, is connected.

The resistor 32 serves to prevent the rectifier grid-current from affecting the bias applied to the amplifier tubes.

The volume-control tube is supplied with variable grid bias potential through a connection, including a resistor 39, which extends between the grid thereof and a movable contact arm 41 associated with a portion of the voltage dividing resistor that is more negative than the point 35 to which the cathode is connected.

A conductor 43 extends from the plate of the volume-control tube to the grid circuits of preceding amplifying tubes (not shown) for the purpose of supplying an increasing negative bias thereto in response to increasing signal amplitudes and a plurality of conductors 45, 47 and 49, extend from the voltage dividing resistor to the cathode and plates of the said amplifying tubes respectively.

The light-source is preferably disposed in proximity to the rear face of a translucent tuning-indication device 51 or dial, a mask 53 being optionally disposed between the source and the said dial to limit the area illuminated.

In the operation of my improved signal receiving system, the plate of the rectifier or noise suppressor tube 3 is supplied with an alternating potential of 300 volts which potential may, conveniently, be derived from a secondary winding 55 of the power transformer (not shown) which energizes the power rectifier (not shown) to supply the voltage dividing resistor and the cathode heating circuits of the system. The rectifier 3 is normally so biased by adjustment of the points 33 and 17 on the voltage dividing resistor to which the grid and cathode are respectively connected that, when no signal is being impressed upon the input circuit of the volume-control tube from the preceding amplifying tubes, current flows in the output circuit thereof and causes

the light-source to be energized. The fall in potential across the light-source is in such direction as to increase the normal negative potential applied to the grid of the second detector tube to far beyond the cut-off point, thus preventing it from operating.

As soon as a signal of predetermined amplitude is received, increased current flows in the output resistor 31 of the volume-control tube, which functions as an anode-bend detector, causing a drop in potential across the output resistor in such direction as to render the grid of the rectifier more negative. Upon the grid of the thyratron becoming sufficiently negative, the device is rendered non-conductive and output current 15 therefrom ceases.

The cessation of current-flow through the light-source removes the additional negative potential added thereby to the input circuit of the second detector tube, thus permitting the said tube to become operative to demodulate signals impressed upon the input circuit thereof from the preceding amplifying tubes. At the same time, the tuning dial is deprived of illumination, thus indicating that a signal of predetermined amplitude is being impressed upon the second detector tube from the preceding tubes in the system.

It has been found that in the operation of the system described, the grid controlled rectifier device 3, when provided by a type of electrostatically controlled arc rectifier known commercially as a Thyratron, and in conjunction with an input grid circuit filter including a resistor 32, the rectifier device operates with an appreciable hysteresis effect so that the voltage required to start the device is substantially greater than the voltage required to maintain it in operation after it has once been started. This is a desirable characteristic since it tends to stabilize the operation in response to small variations in signal intensity at a critical operating point. In conjunction with a rectifier device of the above type, the filter means, including the resistor 32, is effective as a stabilizing means.

It has also been found that the grid filter means for the signal transmission device, or second detector 5, which grid filter means includes the resistor 13, prevents a rapid change in grid potential and thereby prevents noisy operation 50 of the circuit which would ordinarily be occasioned by too rapid change in the grid potential of the signal transmitting device. With this resistor interposed between the variable source of biasing potential, which in the present example is the indicating lamp 15, and the grid circuit of the device 5, the anode current of the device 5 may be caused to change at a desired slow rate, while at the same time the resonance indicating device 15 may be permitted to operate instantly 60 in response to cut-off control of the rectifier device 3.

The action of the device 5 may be controlled by the filter device 13 and the action may be made such that the noise of operation may be entirely eliminated. This, however, does not prevent an indication of signals tuned in, for the reason that the indicating device 15 is responsive instantly to signals. The system just includes a quick acting device and a slow acting detector device.

It also lies within the scope of my invention to substitute a resistor for the light-source 15 and to so control the application of energy to the said source from an appropriate battery or the like, 75

by means of relays or equivalent devices, that the dial is illuminated only when the signal is properly tuned in and not during the tuning operation, as just described.

5 It also is feasible to provide a plurality of light-sources, one or more of which are under control of the rectifier, whereby the dial is generally illuminated during the tuning operation and a circumscribed area thereof, on which call-letters 10 are visible, is illuminated by light of a different color or by light from an auxiliary, constantly energized source, when the tuning operation is complete.

It will be apparent, from the foregoing, that I 15 have, by my invention, provided a system whereby the operation of tuning a signal receiving system is rendered entirely free from background noise and from interferences by signals emanating from undesired stations, and one whereby a 20 positive indication of the presence of a desired signal is given.

My improved system is also adaptable to power-control by incoming radio signals. In such event, the tuning is fixed and the rectifier output current is used for the actuation of the control-circuits.

Although I have illustrated and described a specific embodiment of my invention, many modifications thereof will be apparent to those skilled 30 in the art to which it pertains. My invention, therefore, is not to be limited except insofar as is necessitated by the prior art and by the spirit of the appended claims.

I claim as my invention:

35 1. In signal receiving apparatus including demodulating means, means for supplying signal potentials to said demodulating means including an adjustable tuning reactor, and signal responsive means for applying an additional potential 40 to said demodulating means to render said demodulating means substantially inoperative during adjustment of said reactor and for restoring said demodulating means to operation in response to signals of a predetermined amplitude.

45 2. In signal receiving apparatus including a detector, means for supplying signal potentials to said detector including an adjustable reactor, and signal responsive means for applying an additional potential to said detector to render said 50 detector substantially inoperative during adjustment of said reactor and for restoring said detector to operation in response to signals of a predetermined amplitude.

3. In combination, an amplifier, a detector, 55 means for supplying signals to said detector and signal responsive means for applying a controlling potential to said detector to render said detector inoperative when the signal delivered thereto by said amplifier is below a pre-determined amplitude and for restoring said detector to operation when the signal delivered thereto is above said amplitude.

4. In combination, an amplifier, a detector, 60 means for supplying signal potentials to said detector, and separate signal responsive means for applying an additional potential to said detector to render said detector inoperative when a signal delivered thereto by said amplifier is below a pre-determined amplitude, said means 65 being responsive for restoring said detector to operation when said signal is above said amplitude, said means including a grid-controlled rectifier device, and a resistor filter means in the grid circuit of said device.

75 5. In combination, an amplifier, a detector,

means for supplying signal potentials to said detector, separate signal responsive means for applying an additional potential to said detector to render said detector inoperative when a signal delivered thereto by said amplifier is below a predetermined amplitude, said means being responsive for restoring said detector to operation when said signal is above said amplitude, and a tuning indicator including a current responsive light source having a potential drop producing impedance for providing said additional controlling potential.

6. In signal receiving apparatus including demodulating means, means for supplying signal potentials to said demodulating means including an adjustable tuning reactor, signal responsive means for applying an additional potential to said demodulating means to render said demodulating means substantially inoperative during adjustments of said reactor and for restoring said 20 demodulating means to operation in response to signals of a predetermined amplitude, and electrical means in circuit with said last named means providing a light source for indicating the tuning of the apparatus, the said light source being 25 connected with and under the control of the said means for controlling the demodulator means.

7. In a signal-receiving apparatus, a detector device having a control grid circuit, a light source connected in said circuit, a time delay filter means 30 in said circuit between said light source and said detector, a grid controlled rectifier device connected in circuit with said light source to control the flow of current therethrough, circuit means for supplying alternating current through said 35 rectifier device to said light source, a signal responsive automatic volume control means having an output circuit, a grid circuit for said rectifier device connected with said output circuit to receive controlling potentials therefrom, and 40 means for supplying signals to said automatic volume control means, said means including a tuning reactor.

8. In a radio signal receiving system having automatic volume control means, the combination 45 of a detector tube, means providing a biasing potential normally rendering said detector inoperative to rectify signals, and means including a grid controlled rectifier device controlled by said 50 automatic volume control means for reducing said biasing potential to a value whereat said detector is operative in response to signals of a predetermined amplitude.

9. In signal receiving apparatus, tuning means, a potential source, tuning indication means operatively connected with said tuning means, a light source so disposed as to be capable of illuminating at least a portion of said indicating means, signal controlled means for substantially depriving said light source of potential when said 60 tuning means is adjusted to sympathy with a desired signal, and an electric discharge device in the signal channel of said apparatus, said device having a control grid circuit, said light source being included in said grid circuit and providing potential-drop producing impedance means 65 therein, thereby to control said device in transmission of signals.

10. In a radio signal receiving system having automatic volume control means, the combination 70 of a detector tube, means providing a biasing potential normally rendering said detector inoperative to rectify signals, means including a grid controlled rectifier device controlled by said automatic volume control means for reducing said 75

biasing potential to a value whereat said detector is operative in response to signals of a pre-determined amplitude, and said last named means further including an indicating lamp in series 5 with said rectifier device having an impedance from which said potential is derived.

11. In a signal-receiving apparatus, the combination with a tuning indicator and an electric discharge device in the signal circuit of said 10 apparatus for controlling the transmission of signals therethrough, said device having a control grid circuit, of a lamp connected in said grid circuit and associated with said tuning indicator, said lamp being adapted to provide a potential drop in operation sufficient to bias said device to a point whereat it is inoperative to transmit signals, a time delay filter means interposed between the lamp and said device, an electrostatically controlled arc rectifier device connected in circuit with said lamp for controlling the flow of current therethrough, a control grid circuit for said rectifier device, and signal responsive means connected with said grid circuit for supplying controlling potentials thereto of a 15 magnitude sufficient to bias said device to cut-off in response to signals above a predetermined amplitude.

12. In a signal-receiving apparatus, means for controlling the transmission of signals through 30 said apparatus and for providing a visual indication of said signals, said means including an electric tuning indicator lamp, a signal controlled rectifier device in circuit with said lamp for supplying current thereto, and an electric discharge signal amplifier device in the signal transmission channel of the apparatus connected with said lamp for receiving a biasing potential therefrom.

13. In a signal-receiving apparatus, means for 40 controlling the transmission of signals to said apparatus and for providing a visual indication of said signals, said means including an electric tuning indicator lamp, a signal controlled rectifier device for supplying current thereto, an electric discharge signal amplifier device in the signal transmission channel of the apparatus connected with said lamp for receiving a biasing potential therefrom, a control grid circuit for each of said devices, and a filter means in each 45 of said circuits.

14. In a signal-receiving apparatus, the combination of a signal indicating circuit, a grid controlled rectifier device for supplying current thereto, a potential drop producing element in 55 said circuit, an electric discharge signal amplifier device connected with said element to receive a controlling potential therefrom, said device being in the signal channel of the receiving apparatus thereby to control the flow of signals therethrough, and signal responsive means for controlling said rectifier device, thereby to control the flow of current through said device to said indicating circuit.

15. In a signal-receiving apparatus, the combination of a signal responsive volume control means having an output circuit, a grid controlled rectifier device having its control grid connected with said output circuit, an alternating current 65 supply circuit for said device, an indicating device in said circuit, a signal circuit, an electric discharge device in said circuit, said device having a grid connected with said indicating device, and said last named device being adapted to 70 produce a potential drop sufficient to bias said

discharge device whereby it becomes inoperative to transmit signals through said signal circuit.

16. In a radio receiver, a noise-suppressor tube having input and output circuits, a controlled tube connected to the output circuit of said noise-suppressor tube, said controlled tube being adapted to amplify the signals being reproduced by said receiver, means for impressing upon the input of said noise-suppressor tube a voltage representative of the average direct-current signal component of the received signal, the input and output circuits of said noise-suppressor tube and the characteristics of both of said tubes being so chosen that when the said direct-current component falls below a predetermined amount the 10 controlled tube is biased to cut off, and means for regulating the action of said noise-suppressor tube, and thereby regulate the level of cut-off of said suppressor tube and permit signals of any 15 desired intensity to be reproduced.

17. In a radio receiver, a controlled tube adapted to amplify the signals reproduced by said receiver, a noise-suppressor tube being adapted to control the amplification of said controlled tube and having input and output circuits, means for impressing upon the input of said noise-suppressor tube a voltage representative of the direct-current component of the received signal, whereby, in the absence of a signal, the noise-suppressor tube will prevent amplification by said controlled tube of stray impulses and noises, and means for regulating the action of 20 said noise-suppressor tube.

18. In a radio receiver, a controlled tube adapted to amplify the signals reproduced by 35 said receiver, a noise-suppressor tube being adapted to control the amplification of said controlled tube and having input and output circuits, means for impressing upon the input of said noise-suppressor tube a voltage representative 40 of the direct-current component of the received signal, whereby, in the absence of a signal, the noise-suppressor tube will prevent amplification by said controlled tube of stray impulses and noises, and means for regulating the action of 45 of said noise-suppressor tube, and thereby regulate the level of cut-off of said suppressor tube to permit signals of any desired intensity to be reproduced.

19. In a radio receiver, automatic means for controlling the amplification of the received radio signals, a controlled tube adapted to amplify the signals further, a noise-suppressor tube having input and output circuits, said noise-suppressor tube being adapted to control automatically the 55 amplification of said controlled tube, means for impressing upon the input of said noise-suppressor tube a voltage representative of the direct-current component of the amplified signal, whereby, although the amplification is maximum 60 in the absence of a signal, the noise-suppressor tube will prevent amplification by said controlled tube of stray impulses and noises, and means for regulating the action of said noise-suppressor tube, and thereby regulate the level of cut-off of 65 said suppressor tube to permit signals of any desired intensity to be reproduced.

20. An electric circuit arrangement including a source of carrier-frequency signal voltage, a first vacuum tube having at least an anode, a 70 cathode, and a control electrode, circuit arrangements for impressing an alternating voltage derived from said signal voltage between said cathode and control electrode, a second vacuum tube having at least an anode and a cathode, 75

means for producing in the output circuit of said second vacuum tube a uni-directional potential which varies in accordance with the amplitude of said carrier-frequency signal voltage, a connection between a point of said output circuit and a control electrode of said first tube, said point being negative with respect to the cathode of said first tube in the absence of a signal, and becoming less negative when the signal strength increases, whereby the effective impedance of said first tube is decreased as said signal voltage increases, and variable means for determining the carrier-frequency signal strength which is required to substantially decrease the internal impedance of said first tube.

21. In a radio receiver which includes a plurality of amplifying tubes, the combination of means for developing a direct-current potential, means for varying said potential inversely in accordance with variations in a radio-frequency current received by said receiver, circuit connections for applying said potential in a negative sense to one of the amplifying tubes of said receiver, the polarity of said potential being such that when said radio-frequency current increases from a low value, said potential becomes more positive, and means for altering upon said amplifier the effect of the variations in radio-frequency current as transmitted by said direct-current potential.

22. In a radio receiver tunable over a range of carrier-frequency channels, a system for suppressing inter-channel disturbances and signals having voltages below a predetermined level, comprising an amplifying tube, means for applying a biasing voltage to a control electrode of said tube of a negative value sufficient to prevent said tube from transmitting signals, supplemental means for deriving from the received signal a uni-directional voltage which varies as the strength of said signal, means for applying said uni-directional voltage to said control electrode in the polarity which renders the bias on said control electrode less negative, and adjustable means for regulating said predetermined voltage level below which disturbances and signals are suppressed.

23. In a radio receiver tunable over a frequency range, means for suppressing interchannel disturbances and voltages below a cut-off level, said means comprising a first tube having input and output circuits and a first resistor included in said output circuit, a second tube having a control electrode connected to a point of said first resistor, said control electrode having impressed thereon a bias voltage which is more negative than that which permits said second tube to transmit signals, a rectifier for deriving from received signals a uni-directional voltage which varies as the strength of said received signals, a second resistor connected in circuit with said rectifier across which said uni-directional voltage is developed, and a connection from said second resistor to the input circuit of said first tube, whereby fluctuations of the uni-directional voltage across said second resistor in response to said received signals produce inverse fluctuations of the voltage across said first resistor and thereby render the bias on said second tube less negative and thus enable said second tube to be operative when said received signals rise above the cut-off level, and adjustable means for selecting said cut-off level.

24. In a radio receiver, a rectifier, a controlled tube adapted to amplify the signals being repro-

duced by said receiver, a noise-suppressor tube being adapted to control the amplification of said controlled tube and having input and output circuits, and means for impressing upon the input of said noise-suppressor tube a voltage representative of the direct-current component of the rectified signal, and a connection from the output circuit of said noise suppressor tube to an initially negatively biased control element of said controlled tube for regulating the bias of said control element, the polarity of said connection being that which causes said bias to become less negative to reduce the internal impedance of said controlled tube when the signal voltage rises above a low value which is below that desired for normal reception, whereby, in the absence of a signal, the noise-suppressor tube will prevent amplification by said controlled tube of stray impulses and noises.

25. An electric circuit arrangement including in effect two electron discharge valves, input terminals for said arrangement, circuit connections for supplying a carrier frequency voltage to said input terminals depending upon the strength of an impressed signal, means for developing a uni-directional output component at a first of said valves which varies upon variation of the strength of said voltage, and a connection which impresses at least a portion of said uni-directional component upon a control element of said second valve in the polarity which causes said control element to become more positive when the signal strength increases, whereby the internal impedance of said second valve is decreased as the strength of said impressed signal is increased, and means for impressing an alternating current voltage upon the input of said second valve.

26. In a radio receiver, a carrier-frequency amplifier for amplifying received signals, a second amplifier operating at a lower frequency than said carrier-frequency amplifier for further amplifying said signals, a rectifier responsive to the carrier frequency signals for producing a rectified voltage, an automatic volume control system operable by said rectified voltage for controlling the bias of a control electrode of said carrier-frequency amplifier, a resistor across which there is developed in response to said rectifier a unidirectional voltage which varies as the strength of said carrier frequency signals when the signals are of lower intensity than that required for normal operation of said receiver, and a noise-suppressing connection from a point of said resistor to a control electrode of said second amplifier, said latter electrode being at such a potential that said noise-suppressing connection biases said control electrode of said second amplifier more positively when the received signal intensity rises above a predetermined value, whereupon the effective impedance of said second amplifier decreases and signals are readily transmitted therethrough.

27. In a carrier frequency signaling system including two electron discharge valves, a circuit arrangement through which alternating current voltages are supplied to the input of each of said valves, means including an impedance for developing at the output of a first of said valves a uni-directional voltage responsive to said carrier frequency, which uni-directional voltage varies upon variation of the strength of said impressed signal, a connection from a point of said impedance to a control element of said second valve, said control element having impressed thereon a biasing voltage which is greatly nega-

tive when said alternating voltage intensity is relatively small, the polarity of said point being that which causes said element to become less negative when the alternating current voltage increases, whereby the internal impedance of said second valve is decreased as said alternating current voltage increases, and means for adjustably determining the alternating current voltage intensity above which said internal impedance is substantially decreased.

28. In a carrier signaling system, a vacuum tube, a rectifier having its input circuit connected to a point in said system ahead of said tube, means for producing a direct-current potential in the output of said rectifier which varies as the strength of the carrier wave supplied thereto, means for applying a biasing voltage derived from said direct-current potential to a control element of said tube, whereby the impedance of said tube is effectively decreased when the strength of the carrier wave rises above a predetermined cut-off level, and variable means for determining said predetermined cut-off level.

29. In a radio receiver, a receiving network tunable to an incoming signal, a source of automatic volume control potential for determining the response level of said receiver when tuned, an illuminable tuning indication device for determining said signal, and means responsive to variations in said automatic volume control potential for illuminating said tuning indicator device in one manner when said network is tuned and in a different manner when it is detuned.

30. In a radio receiver of the type including a signal tuning device, said device being provided with an illuminable tuning indication dial, an automatic volume control arrangement for determining the response level of said receiver when tuned to a desired signal carrier by said tuning device, a current responsive light producing de-

vice disposed in a position adjacent to the dial to illuminate at least a portion thereof, and means, responsive to the operation of the volume control arrangement, for controlling the current flow through said light producing device whereby a resonance condition of the receiver is determined.

31. In a radio receiver of the type including a signal tuning device, said device being provided with an illuminable tuning indication dial, an automatic volume control arrangement for determining the response level of said receiver when tuned to a desired signal carrier by said tuning device, a current responsive light producing device disposed in a position adjacent to the dial to illuminate at least a portion thereof, and means, responsive to the operation of the volume control arrangement, for controlling the current flow through said light producing device whereby a resonance condition of the receiver is determined, and additional means for illuminating said dial disposed adjacent the latter.

32. In a radio receiver of the type including a signal tuning device, said device being provided with an illuminable tuning indication dial, an automatic volume control arrangement for determining the response level of said receiver when tuned to a desired signal carrier by said tuning device, a current responsive light producing device disposed in a position adjacent to the dial to illuminate at least a portion thereof, and means, responsive to the operation of the volume control arrangement, for controlling the current flow through said light producing device whereby a resonance condition of the receiver is determined, and an apertured screen disposed between said light producing device and the dial to define an area of illumination on the dial.

GEORGE LISLE BEERS. 40
